(57) **CLAIM**

The ornamental design for a daytime running light arrangement for a headlight, as shown and described.

DESCRIPTION

FIG. 1 is a front left perspective view of a daytime running light arrangement for a headlight according to the present invention.

FIG. 2 is a front view of the daytime running light arrangement shown in FIG. 1.

FIG. 3 is a left side view thereof.

FIG. 4 is a top view thereof.

FIG. 5 is another front view thereof shown in use; and,

FIG. 6 is a front view mirror image thereof shown in use. The broken lines illustrating environmental structure form no part of the claimed design. The deemphasized portions form no part of the claimed design.

1 Claim, 6 Drawing Sheets
